UNITED STATES PATENT OFFICE.

HARRY L. COMPTON, OF WASHINGTON, DISTRICT OF COLUMBIA, ASSIGNOR TO AMERICAN DAIRY SUPPLY COMPANY, OF AUGUSTA, MAINE, A CORPORATION OF MAINE.

MECHANISM FOR PACKING DISKS AND THE LIKE.

1,113,932.

Specification of Letters Patent.

Patented Oct. 13, 1914.

Application filed March 12, 1913. Serial No. 758,866.

To all whom it may concern:

Be it known that I, HARRY L. COMPTON, a citizen of the United States, residing at Washington, District of Columbia, have invented certain new and useful Improvements in Mechanism for Packing Disks and the like, of which the following is a specification.

This invention involves certain improvements in and relating to packing disks and the like; and the objects and nature of the invention will be readily understood by those skilled in the art in the light of the following explanation of the accompanying drawings illustrating what I now believe to be the preferred embodiments from among other formations, arrangements and constructions within the spirit and scope of this invention.

20 The invention consists in certain novel features in construction and in combinations and arrangements as more fully and particularly set forth and specified hereinafter.

Referring to the accompanying drawings:—Figure 1, is a front elevation of apparatus embodying my invention. Fig. 2, is a side elevation thereof. Fig. 3, is a vertical central section in the plane of the line 3—3, Fig. 1. Fig. 4, is a top plan view of the disk feeding and tube filling mechanism. Fig. 5, is a sectional view, on an enlarged scale, taken in the plane of the line 5—5, Fig. 2, looking in the direction of the arrow.

In the drawings, I show an upright bed or frame 1, mounted on and rising from a pedestal 2. The bed 1, carries disk making mechanism involving generally the elements and arrangements approximately as disclosed by Patent No. 927,002, issued July 6, 1909 to American Dairy Supply Co. as the assignee of F. L. Nichols for machine for making cover or closing disks.

In the machine illustrated, the ribbon *a* of disk stock is arranged in front of the bed 1, and the feed rolls 3, printing rolls 4, stapling and handle applying mechanisms 5, and punch or die 6, are carried by and arranged in front of said bed. The wire *b*, from which the staples are made is also arranged in front of said bed and is fed forward step by step into the stapling and handle forming and applying mechanisms

by the reciprocatory wire feeder 7. The ribbon *c*, of handle stock, is fed forward through said bed, from a point in rear thereof, to the handle forming and stapling mechanisms, with a step by step movement, by feed rolls 8.

In the particular example illustrated, spaced areas of the ribbon of disk stock, are successively imprinted, and handles are clipped to the stock in said areas successively, and said areas successively pass under the vertically movable punch 6, and over the annular die 9, and the punch and die cooperate in cutting the complete disks from the ribbon of disk stock. The die 9, is formed in or carried by the die block 10, and this die block is formed with a vertical discharge passage 11 (surrounded at its upper end by die 9) opening through the under side of the block. The punch 6 cuts out the disks and forces them down into said discharge passage, so that disks are dropping from the lower end of the passage as the freshly cut disks are forced into the upper end of the passage.

The feed rolls 3, feed the ribbon of stock *a*, forwardly with a step by step movement, and while the ribbon is at rest a handle is being applied to one previously printed area thereof, and a disk is being cut from the area thereof to which a disk had been applied by the previous operation of the handle making and stapling mechanism.

However, my present invention is not limited to the mechanisms so far described, nor is it limited to handling disks provided with tabs or other handles.

If the completed disks are to be treated with material (paraffin for instance,) to render them non-absorbent, I provide suitable mechanism for this purpose although my invention is not so limited. For instance, in the particular example illustrated, I show an open top paraffin pot 12, provided with suitable means for supplying the necessary heat to keep the paraffin in a liquid condition. This pot is arranged in front of the pedestal and is usually secured thereto and supported thereby below the level of the discharge end of passage 11, and a distance in front thereof. In the pot I show a horizontal transversely arranged rotary paraffining

roll 13, having an absorbent material surface dipping into the liquid paraffin in the pot. This roll is carried and driven by a suitable shaft 14, carried by the pot and extending to the exterior of the ends thereof.

At one end this shaft is provided with pulley 15, to which power is applied for rotating roll 13, so that its upper surface will move forwardly.

10 An absorbent-material-surface paraffining and pressure roll 16, is arranged above and coöperates with and is driven by roll 13. The pressure roll shaft is carried by adjustable boxes confined in brackets 17, fixed to 15 and rising from the pot ends.

A stripper roll 18, is shown engaging the upwardly moving rear side of the paraffin roll 13, to remove surplus paraffin therefrom.

Means are provided for receiving the completed disks discharged from the lower end 20 of passage 11, and delivering the same one at a time onto the forwardly moving upper surface of the paraffining roll 13, so that the disks will be carried forward between the 25 paraffin saturated surfaces of rolls 13, 16, and will absorb the desired quantity of paraffin therefrom.

In the particular example illustrated, although my invention is not limited thereto, 30 I show conveying means for this purpose comprising a downwardly and forwardly inclined chute or trough 19, having a flat floor and vertical longitudinal edge walls spaced apart a distance slightly greater than the 35 diameter of the disks. This chute is carried by an elongated supporting frame 20, at its upper portion having suitable supporting brackets 21, secured to any support such as the bed 1, or the pedestal 2. The chute is 40 also supported by the transverse rotary cross shaft 22, mounted in and passing through the lower end of frame 20, and mounted in and supported by the brackets 17.

The upper end of the frame 20 is formed 45 with longitudinal slots, receiving the transverse shaft 23, which is adjustable longitudinally of the chute and is held in the desired adjustment by adjusting and stop screws 24. This shaft 23, carries idler roll 50 25, mounted to rotate on the shaft between the longitudinal sides of frame 20. This rotating roll is located directly below the discharge passage 11, so that the disks falling from said passage will drop onto said 55 roll and be thereby directed forwardly in the chute. The upper surface of this roll 25 is moving forwardly and the disks are thereby thrown forwardly and properly started on their course down the chute. The roll is 60 intended to prevent the disks wedging or becoming congested at the upper end of the chute, and also to prevent the disks assuming vertically disposed or edgewise positions at the upper end of the chute.

65 I arrange an endless traveling flexible

disk-propelling connection centrally and longitudinally of the chute and extending from the roll 25 to the shaft 22. In the particular example illustrated, this connection is formed by a comparatively narrow chain 70 26, mounted on the roll 25, and on a roll 27, fixed on the shaft 22. The roll 27 is located in a slot or opening in the lower end portion of the floor of the chute and corresponds to roll 25. These rolls 25, 27, have central annular reduced portions receiving said chain 75 and containing the sprocket wheels 28, on which the chain is mounted.

The upper ply of the chain travels downwardly on the floor of the chute while the 80 lower ply of the chain returns below the chute. The chain is driven by shaft 22, and can be tightened or loosened by adjusting shaft 23, through the medium of screws 24.

The chain tends to maintain the disks in 85 flat position in the chute and propels the disks downwardly and prevents them from congesting or unduly collecting in the chute. The lower end 29 of the chute floor, below roll 27, overlaps the paraffining roll 13, and 90 delivers the disks thereonto. The forwardly moving surface of the lower roll 27, imparts the final propelling movement to the disks to carry them to the paraffining rolls.

The propelling devices are particularly 95 designed to prevent congestion of the disks between the discharge from the punch and the paraffining rolls, and to cause delivery of the disks one at a time and in flat or approximately horizontal position to said rolls. 100

Any suitable means can be provided for driving the disk propelling chain, although in the present instance, I show the same driven from the paraffining roll shaft 14, by driving connection 30, mounted on suitable 105 sprocket wheels on shafts 14 and 22.

It is advantageous for various purposes to pack disks (particularly so-called caps for closing receptacles containing milk or other food products) in tubes for handling and 110 shipment. It is desirable so far as possible, to prevent the disks from coming in contact with human hands during and after the process of manufacture and until the disks are in position sealing food products in receptacles. Where the disks are to be applied to the receptacles by machines it is 115 desirable to have the disks packed in long tubes capable of being placed in the machines to serve as supply magazines from 120 which the machines can feed the disks, or from which the disk magazines of the machines can be readily filled.

My present invention relates particularly to means for receiving the disks from the 125 disk or cap making machine, and packing the same in tubes, so that the disks can be made and packed without being touched by the hands of the operators.

I provide means to receive the disks from 130

the rolls 13, 16, (which constitute feed rolls, irrespective of the fact that they also serve to apply paraffin to the disks), and to force a column of said disks into a packing tube 5 removably held in position to receive such disks.

In the particular example illustrated, I show a chute embodying a constantly and rapidly downwardly moving floor receiving the disks from the roll 13, and delivering the same edgewise or approximately vertically onto and arranged transversely of an elongated upwardly extending guideway or floor, arranged approximately at right angles to said chute just mentioned, and into a screw feed mechanism for forcing said disks upwardly and longitudinally of said guideway with their lower edges sliding along the same and with the disks spaced apart and approximately parallel, and finally bringing said disks together into a column and forcing said column through a cylindrical guide neck or feed nozzle for guiding the disks into a packing tube 25 removably held in alinement with said nozzle.

A removable frame or bracket 32, is provided to carry the devices for receiving the disks from roll 13, and for packing the disks in tubes. This bracket can be removably bolted or otherwise secured to the paraffin pot and is shown extending downwardly and forwardly at an angle from the front top edge of said pot. This bracket carries a chute or guideway extending downwardly and forwardly at an angle from the paraffining roll 13, and having a flat floor the upper end of which overhangs the top forwardly moving surface of the roll 13, to strip the closure disks therefrom, so that said disks 35 will move down said chute to the feed screw mechanism at the lower end thereof. The flat inclined floor of this guideway is composed of the stationary portions 33, and the moving portion 34. The chute has edge 40 walls 35, extending longitudinally thereof, and if so desired said chute can be also provided with a front guard wall 36, spaced forwardly a distance from the floor of the chute.

50 At the upper end of the chute a stationary plate forming a portion of the flat floor 33, overlies the top surface of roll 13, and also the top edge portion of the floor member 34, overlies the top surface of roll 13. The moving member 34, is formed by a flat circular rotary plate or disk carried by a short shaft 37 mounted in the bracket 32, and so arranged that the downwardly moving upper surface of the rotary disk will form a portion of the floor of said chute for the purpose of quickly carrying the closure disks downwardly through the chute to prevent congestion therewith in the chute and to maintain the disks in their flat positions and to 55 deliver the same one at a time to the screw

feed mechanism hereinafter more fully described. In the particular example illustrated, the upper end of the floor of the chute that overhangs the surface of the roll 13, to strip the closure disks therefrom 70 is formed by a portion of the stationary floor 33 and by the upper edge portion of the rotary disk 34, said upper edge portion of the disk 34, moving in a direction to carry the closure disks into the open upper 75 end of the chute and downwardly in the chute. The disk 34 is preferably rotated at a comparatively high rate of speed.

The chute just described at its lower outer end terminates adjacent to and above an elongated trough or guideway 38 preferably having a concaved longitudinal upper surface. This trough or slideway can be formed by a bar at its lower end secured to the outer portion of the bracket 32, so as to be rigid 80 therewith and to rise therefrom approximately at right angles to the floor 33, 34 of said chute. The arrangement is such that the closure disks will drop from the lower end of the floor 33, onto the trough 38 in a 90 position transversely of the trough and with their lower edges resting in the trough.

Oppositely rotating right and left hand feed screws 39, are arranged parallel with, above and on opposite sides of the trough 95 or slideway 38 so that each closure disk as it drops from floor 33 will pass into operative engagement with the threads of both feed screws and will be guided thereby onto the trough or slideway 38, and will be maintained in an upright or edgewise position and carried upwardly along said trough by said feed screws. The trough or slideway 38 at its upper end terminates at a cylindrical guide neck or feed nozzle 40, arranged centrally between the upper ends of the feed screw axes and in direct continuation of the path of travel of the closure disks between the feed screw and along the slideway 38, so that the closure disks are 100 successively forced by the feed screws into said nozzle and so that the column or pile of disks in said nozzle is fed or forced upwardly and longitudinally therethrough.

The nozzle 40 is fixed at the upper end of the 115 rigid arm forming the slideway 38, and is provided with opposite lateral projections 41, forming bearings and supports for the upper ends of the axes of the feed screws. The lower ends of the axes of the feed screws 120 are suitably mounted in the bracket 32. At its upper end the nozzle 40, is provided with means such as a spring or split sleeve 42, or the like to removably receive a packing tube and normally hold the same in alinement 125 with the nozzle 40, and forming an upward continuation thereof so that the feed screws will force the column of closure disks upwardly through the nozzle 40, and longitudinally of and within the packing tube. I. 130

usually attach an arm 43, to the arm forming the slideway 38 and in upward continuation thereof to support one or more tube rests 45.

5. In the drawings, I show a packing tube 46 resting in a tube rest 45, and at its lower end removably fitted to the tube holder 42. The tubes 46, are usually composed of comparatively light cardboard and are somewhat 10 similar to common mailing tubes. Each tube preparatory to being applied to the apparatus described to receive a load of closure disks, preferably has one end closed against passage of closure disks therethrough. I 15 prefer to close one end of each tube by crimping. In the drawings, I indicate this crimped end by the reference letter 47. When a packing tube is applied to the apparatus the crimped or closed end 47, is located at the upper end of the tube. Thus the 20 apparatus will force the column of closure disks upwardly in the packing tube until said column encounters and is stopped by the crimped end 47, thereupon the pressure 25 of the feed screws on the column of closure disks will gradually move the packing tube 46 upwardly from the holder 42, and the attendant will thereupon observe that the packing tube is filled with closure disks and 30 ready to be removed from the apparatus, so that an empty packing tube can be slipped into place to receive the column of disks constantly advancing upwardly through the nozzle 40.

35. The attendant in removing the filled packing tube from the holder 42, should slip his finger under the column of receptacle disks in the packing tube to retain the same therein. Usually, this end of the packing tube is 40 then closed by crimping; that is, closed to such an extent as may be necessary to retain the receptacle disks therein. Both ends of the completed filled tubes are usually crimped in the manner indicated by the reference letter 47. This crimping of the tubes 45 can be accomplished if so desired, by a rotary crimping head or cup 48 secured on the outer end of the paraffining roll shaft 14 so as to be readily accessible to the attendant 50 standing in front of the machine. The packing tube having its opposite ends thus turned or crimped in to confine the column of closure disks in the tube, forms and constitutes a most convenient and satisfactory 55 original package of closure disks. This package of closure disks can be most conveniently handled and shipped, and can be easily utilized in capping machinery by cutting off one crimped end or by turning the 60 crimp outwardly so that the closure disks are free to move by gravity from the tube. Even where closure disks are not to be applied by capping machinery, these tubes form a very sanitary and convenient means 65 for packing and handling closure disks.

Any suitable or desirable mechanism can be provided for actuating the rotary disk 34 and the feed screws, although in the present instance, I show the bracket 32, provided with a shaft 50, geared to and driven by the 70 paraffining roll shaft 14, through the medium of a drive chain 51, and appropriate sprocket wheels on the two shafts. The lower ends of the two feed screw axes are geared together to rotate simultaneously in opposite directions and at the same speed by a pair of meshing spur gears 52. The feed screws are driven by the shaft 50, through the medium of the beveled gearing 53. The rotary disk 34 is driven from one of the feed screw axes 75 through the medium of spur gearing 54.

If so desired, a guard or guide 55 can be fixed to the nozzle 40, to depend in rear of the upper ends of the feed screws to hold the closure disks down or forwardly to the 80 trough 38 and aid in guiding the same into the lower end of the nozzle 40.

The upper sides of the feed screws 39, move toward each other and hence downwardly or forwardly toward the slideway or 90 trough 38, and thereby tend to press the caps (disks) forwardly and downwardly to said trough as they move said disks upwardly along the trough. The trough thus serves to align the disks and guide them into 95 the nozzle 40, while the disks are spaced apart and held in lateral alignment by the webs or flanges of the feed screws.

Obviously, the mechanism for packing the disks in columns to enter packing tubes 100 is not limited to any particular cap making mechanism nor to use in connection with such mechanism, nor to the paraffining apparatus disclosed, nor in fact to use in connection with any means for paraffining or 105 otherwise treating closure or other disks or caps.

If so desired, the bracket 32, carrying the mechanism for packing disks, can constitute an attachment readily applicable to and removable from the pot 12, or other support. 110

It is evident that my invention is not limited to handling closure disks or caps, and it is also obvious that various changes, variations and modifications might be resorted to without departing from the spirit and scope of the invention and hence I do not wish to limit myself to the particular 115 mechanical expression of my invention disclosed hereby.

Desiring to protect my invention as broadly as is legally possible, what I claim is:

1. In combination, a nozzle adapted to receive a packing tube in longitudinal continuation thereof, an elongated slideway arranged approximately in longitudinal continuation of said nozzle, a pair of elongated feed screws arranged approximately parallel with said slideway to feed disks along 125 130

- 5 said slideway while maintaining the disks out of contact with each other and in approximately parallel positions with their side faces exposed and to bring said disks together to form a column and to feed the column forwardly through said nozzle and in said tube, and means for delivering disks separately into said screws and onto said slideway.
- 10 2. In combination, a chute to receive disks successively and to deliver the same downwardly, a guideway arranged approximately at right angles to the line of the travel of the disks down said chute and adapted to receive the disks from said chute, a pair of parallel right and left oppositely rotating feed screws arranged parallel with said guide way and adapted to guide and propel the disks along said guideway, while maintaining the disks out of contact with each other, and a nozzle into which the disks are forced by said feed screws.
- 15 3. Means for assembling disks in a stack or column and for feeding said column longitudinally in a packing tube comprising elongated coöperating parallel oppositely rotating right and left hand feed screws and means for alining and guiding the disks while being propelled by said screws, said screws being arranged to feed a series of disks forwardly while maintaining the disks out of contact with each other and with their side faces exposed and to force said disks forwardly when brought together and assembled to form a column.
- 20 4. In combination, a nozzle, means for removably holding a packing tube in alignment with and continuation of said nozzle, and screw feed mechanism for receiving disks and feeding same forwardly and out of contact with each other and then assembling the same in a column and feeding the column longitudinally through said nozzle and into said tube.
- 25 45 5. In combination, a nozzle, means for removably holding a packing tube in longitudinal continuation of said nozzle to receive a column of disks fed longitudinally through the nozzle, and mechanism for separately receiving disks and feeding the same forwardly out of contact with each other and toward said nozzle and then assembling the same to form a column and for feeding the column longitudinally through said nozzle.
- 30 6. In combination, a pair of elongated parallels coöperating, oppositely rotating right and left hand feed screws, means for separately delivering disks between said screws and into operative relation thereto and transversely of the axes thereof, means for guiding and alining the disks while being maintained out of contact with each other and moved forward by said screws, and means for receiving the disks from said screws and successively bringing them to-
- 35 7. In combination, a support, a disk nozzle provided with an overhanging top guard and having means to removably receive a packing tube and hold the same in alignment with and continuation of the nozzle and movable longitudinally from the nozzle, and mechanism for assembling disks together to form a column and delivering the same into a packing tube.
- 40 8. In combination, a rigid longitudinally elongated bar forming a trough, said trough at its outer end being provided with a guide nozzle approximately alined therewith and provided with a longitudinally projecting split sleeve for longitudinally and slidably receiving and removably holding a packing tube in continuation of the nozzle, an arm projecting longitudinally from said bar and provided with a tube rest, and mechanism for feeding disks longitudinally along said trough while maintaining the same separate from each other and approximately parallel and for then bringing said disks together to form a column and for forcing said column of disks through said nozzle and into said tube.
- 45 9. In combination, an inclined frame provided with an upwardly and forwardly extending elongated trough at its upper end provided with a disk guide nozzle adapted to receive a packing tube and to deliver disks thereinto, a feed screw mechanism arranged approximately throughout the length of said trough for moving disks along said trough and into and through said nozzle, a disk chute carried by said frame for discharging disks into said feed mechanism, and actuating gearing carried by said frame.
- 50 10. In combination, a relatively fixed longitudinally elongated disk supporting feed way, mechanism for sliding disks along said way and for maintaining said disks approximately parallel and separated with their side faces exposed and for then bringing said disks together to form a column and for feeding said column longitudinally forward, and means for guiding said column of disks into a packing tube.
- 55 11. In combination, a rigid longitudinally elongated bar forming a trough, said trough at its outer end being provided with a guide nozzle approximately alined therewith and provided with a longitudinally projecting split sleeve for longitudinally and slidably receiving and removably holding a packing tube in continuation of the nozzle, an arm projecting longitudinally from said bar and provided with a tube rest, and mechanism for assembling disks into a column and fore-
- 60 65 70 75 80 85 90 95 100 105 110 115 120 125 130

ing the column forwardly through said nozzle and in said tube.

12. In combination, means for removably supporting a packing tube in longitudinal sliding adjustment, guiding means for assembling and directing a column of disks into said tube, and mechanism for feeding disks to said means while maintaining said disks approximately parallel and spaced 10 apart with their side faces exposed and for simultaneously feeding forward said column of disks.

13. In combination, mechanism for feeding disks forward while maintaining them separated and parallel with their faces exposed, devices for successively feeding disks 15 to said mechanism, and means for assembling said disks from said mechanism to form a column and to guide said column into a packing tube while said column is fed forward by said mechanism.

14. In mechanism for packing disks in tubes, in combination, a disk guide, means for supporting a packing tube in alinement 25 with said guide to receive a column of disks therefrom, said means being arranged to removably support said tube in longitudinal adjustment with respect to said guide, said tube having its outer end closed against 30 passage of disks therefrom and its inner end open to receive the column of disks, whereby the advancing column of disks in the tube will force said tube longitudinally from said guide when the column fills the 35 tube and engages its closed end, said tube then adapted to have its inner end closed against passage of disks, and mechanism for assembling disks to form a column and to force said column forwardly through said 40 guide and into said tube.

15. In mechanism for packing disks in tubes, in combination, a nozzle, and mechanism for assembling disks to form a column and to act on said column with a constant 45 pressure longitudinally thereof to advance said column forwardly through said nozzle, said nozzle formed to slidably receive a disk packing tube in longitudinal continuation thereof to receive said advancing column of 50 disks, said tube being slidably removable longitudinally from said nozzle under the pressure of the advancing column of disks when filled thereby.

16. Disk paraffining means, in combination with mechanism for alining said disks while moving the same forwardly spaced apart and arranged one behind the other with their faces approximately parallel, and means for successively feeding the disks 60 from said paraffining means into operative engagement with said mechanism.

17. Disk paraffining means, in combination with mechanism for alining the disks while feeding the same with their faces ap-

proximately parallel, and a rotating flat- 65 face disk for successively shooting the disks from said means edgewise into said mechanism.

18. In combination, a disk-lining and supporting slideway, oppositely rotating 70 screws extending approximately throughout the length of the slideway and coöperating to aline and hold disks on said slideway and to move the same longitudinally thereof while maintaining the disks one behind 75 the other on the slideway with their faces approximately parallel, and means for successively discharging said disks edgewise between said screws and onto said slideway.

19. In combination, a disk-alining slide-way, a nozzle at the outer end thereof and alined therewith, oppositely rotating screws extending approximately throughout the length of the slideway and coöperating to 85 aline disks thereon and hold the same there-to while sliding the disks along the slide-way with their faces approximately parallel and assembling the disks together and forcing the same through said nozzle as a 90 column, and means for successively feeding disks edgewise to said screws and onto said slideway.

20. In combination, a supporting bracket provided with means for attaching the same 95 to a disk paraffining device, a forwardly and downwardly inclined chute for discharging the disks downwardly from said device embodying an inclined rotary table-disk mounted in said bracket and having a 100 flat face forming a portion of the floor of said chute to receive the disks and successively shoot them downwardly, actuating gearing carried by said bracket for rotating said table disk, and disk conveying means 105 carried by said bracket and into which said disks are successively discharged edgewise by said table disk.

21. A disk paraffining device embodying a horizontal rotating roll over which the 110 disks pass, in combination with a discharge chute for stripping the disks from said roll, said chute including a rotary table-disk having a flat disk receiving face, and means for rotating said table-disk rapidly with respect to said roll for shooting the disks 115 therefrom and through said chute to prevent clogging of the disks in the chute.

22. A disk-paraffining device embodying a horizontal rotary paraffining roll over 120 which the disks are passed, and means for stripping the disks from said roll and shooting them forwardly embodying a rotary table-disk inclining downwardly and forwardly from said roll, and having a flat 125 top face, means to confine the disks on and approximately parallel with the downwardly and forwardly moving portion of

the top face of said table disk and to strip and guide the disks therefrom.

23. A disk paraffining device embodying a horizontal rotary paraffining roll over which the disks pass horizontally in combination with means to strip the disks from said roll and shoot the same forwardly therefrom embodying a rotary forwardly extending table disk overlying the discharge

side of said roll and receiving the disks to therefrom.

In testimony whereof I affix my signature in presence of two witnesses.
